UNITED STATES PATENT OFFICE.

GUSTAF DALÉN, OF STOCKHOLM, SWEDEN, ASSIGNOR TO AMERICAN GASACCUMULATOR COMPANY, OF PHILADELPHIA, PENNSYLVANIA, A CORPORATION OF NEW JERSEY.

LIGHT-SIGNAL APPARATUS.

1,079,544.

Specification of Letters Patent. Patented Nov. 25, 1913.

Application filed April 23, 1912. Serial No. 692,590.

To all whom it may concern:

Be it known that I, GUSTAF DALÉN, a subject of the King of Sweden, residing in Stockholm, Sweden, have invented certain 5 new and useful Improvements in Light-Signal Apparatus, of which the following is a specification.

My invention relates to light signal apparatus of the general character of that 10 illustrated in certain of my previous patents, as for instance, United States Patent No. 952,420, issued to me March 15, 1910, and it has for one of its objects to provide an improvement in the construction of 15 means for varying the lengths of the periods of darkness or for varying the lengths of the light periods of a light signaling apparatus.

Other objects and advantages of my invention will be referred to or will be apparent from the detailed description of my invention which follows.

My invention consists of mechanism which is adapted to vary the lengths of the dark periods or the light periods of a light 25 signal apparatus, which mechanism is adapted to be operated by means of the increase and decrease of gas pressure in the gas receiving chamber of the apparatus.

My invention also comprehends the combination and arrangement of parts as hereinafter described and as particularly pointed out in the claims.

In the accompanying drawings I have 35 illustrated convenient forms of embodiments of my invention but it will be understood that changes in the details of construction and in the form and relative arrangement of the parts may be made within the scope of the claims without departing 40 from my invention.

In the drawings to which reference should be had for a full understanding of my invention,—Figure 1 is a vertical sectional view, taken on the line 1—1 of Fig. 2, of 45 a construction embodying my invention; Fig. 2 is a top plan view thereof with the diaphragm cover removed therefrom and with certain parts of the casing broken away and shown in section; Fig. 3 is a 50 transverse sectional view taken on the line 3—3 of Fig. 1; Fig. 4 is a transverse sectional view taken on the line 4—4 of Fig. 1; Fig. 5 is a transverse sectional view taken on the line 5—5 of Fig. 1; and Fig. 6 is a

top plan view similar to Fig. 2 showing a 55 slight modification in the construction.

Referring to the drawings, 1 designates a casing closed by means of a diaphragm 2, the outer edges of which are located upon the upper edge of the casing 1 and secured thereto by means of a clamping ring 3 held in clamping position by means of the screw bolts 4. The diaphragm is provided at its center with a downwardly depending member 5 having an elongated slot or opening 6 therein through which the end of a rod or bar 7 projects. The said bar is pivotally mounted upon a pivot 8 upon the upper end of the upturned portion 9 of the member 10 secured to the bottom of the casing 1. 70 The bar 7 is pressed downwardly by means of a spring 15 the outer ends of which are coiled around the pivot 8. The bar 7 also extends through an opening in a block 16 secured to the valve plate 17 which is pivoted in a known manner upon the pointed ends of the bolts 18 which are secured in the upturned end portion 9 of the member 10. An opening 20 is provided through the block 16 at right angles to the opening therein 80 through which the bar 7 extends and through the said opening 20 a wedge or take-up block 21 passes which wedge is jointed to an arm 22 which is pivoted on a stud 23 and is pressed against the inner 85 end of an adjusting screw 24 by means of a spring 25 as is shown in the drawings. The construction of the connection between the diaphragm and the valve plate 17 provides a certain amount of lost motion and 90 by adjusting the position of the wedge or take-up block 21 the amount of such lost motion is varied and by thus varying the amount of the lost motion the lengths of the light and dark periods of the apparatus are 95 varied in a known manner.

As in the previous constructions of this character invented and patented by me, a gas outlet 30 extends from the chamber within the casing 1 to a burner (not shown) 100 and by the opening and closing of the said pipe the light and the dark periods of the apparatus are produced. The main gas supplying pipe 31 for supplying gas to the casing chamber is connected with a valve seat 32 the opening in which is adapted to be 105 opened and closed by means of the valve plate 17. The outlet pipe 30 is connected

with a valve seat 33 having an opening therein which is also opened and closed by means of the valve plate 17 in a known manner. The valve plate oscillates in a known manner between the valve seats 32 and 33. A spring 35, also of known construction and action, operates to hold the valve downwardly upon the valve seat 33.

In the operation of the device as thus far described, it will be understood that as in previous constructions when the valve plate is in the position indicated in Fig. 3 the gas is flowing in through the supply pipe 31 and that as it continues to flow into the chamber of the casing 1 the diaphragm cover 2 rises and in rising, by reason of its connection with the valve plate 17, lifts the latter out of engagement with the valve seat 33 to open the said valve and carries the same against the valve seat 32 to close the opening therein and thus cut off the supply of gas through the pipe 31. The opening in the valve seat 33 being thus opened the gas escapes through the pipe 30 to the burner and the light from the latter gives a light period.

It is desirable to vary the intervals of darkness between the light periods at times so as to render the signal light at a certain place or station of distinctive character. As a means for effecting that result, I have provided an auxiliary gas supplying pipe 40 which communicates with a small chamber 41 in a valve casing 42 which is supported upon the member 10. The said valve casing is provided with an opening which is adapted to be opened and closed by means of a valve plug 43 having a cone-shaped surface 44 which is adapted to be seated upon a correspondingly shaped surface in one side of the casing 42, as is shown in Fig. 4. The valve plug 43 is pressed against its seat in the valve casing 42 by means of a spring 45. The valve plug is provided with a stem 46 which is adapted to coöperate with the valve plate 17 of a member controlled thereby for the purpose of causing movement of the said valve plug 44 to open and close the valve opening in the valve casing 42. In the construction as illustrated, I have provided a ratchet wheel 50 which is supported upon a bracket 51 carried upon the valve plate 17. The said ratchet wheel is provided with perforations 52 which are located at intervals therein at equal distances from its axis. Means is provided for causing rotation of the said ratchet wheel 50 and as it rotates the perforations 52 are moved consecutively over and into alinement with the valve stem 46. When the said valve stem is in alinement with a perforation 52 and the valve plate 17 is moved downwardly, the said stem enters such perforation and the result is that the valve plug 44 is not actuated and consequently it re-

mains in position to close the opening from the valve chamber 41. However, if the ratchet wheel 50 is in such position that a perforation 52 is not in alinement with the valve stem 46 the latter together with the valve plug 44 is depressed with the result that the opening from the valve chamber 41 is opened and as a result gas enters the valve chamber in the casing 1 through the pipe 40. It will be seen, therefore, that at certain times both the main supply pipe 31 and the auxiliary pipe 40 are open so that gas is flowing into the chamber of the casing 1 simultaneously from said pipes, but that at other times the main supply pipe only is opened when the valve plate 17 moves downwardly on to the seat 33.

As a means for causing rotation of the ratchet wheel 50 I provide a rod 60 the inner end of which is supported upon a bracket 61 upon the opposite sides of which collars 62 are provided which may be employed to limit the movement of the said rod 60. I have also secured to the rod 60 a spring 63 which extends laterally from the said rod 60 and engages the teeth upon the ratchet wheel 50 as is shown in the drawings. The opposite end of the rod 60 is connected to a diaphragm 65 in an opening in the side of the casing 1. It may be noted here that reverse or backward movement of the ratchet wheel 50 is prevented by means of a spring-pressed pawl 66.

In the construction as illustrated in Figs. 1 and 2, I have provided just inside of the diaphragm 65 a member 67 which acts as a support or abutment for a spring wire 70 which is coiled around the rod 60 and the other end of which presses against a plate 71 secured upon the said rod.

The pressure and the reduction of pressure of the gas in the chamber of the casing 1 is the means relied upon for causing the actuation of the ratchet wheel 50. When the valve for controlling the outflow of gas through the pipe 30 is closed and the gas is entering the chamber of the casing 1 through the supply pipe 31 or simultaneously through the said pipe and the auxiliary gas supplying pipe 40, the diaphragm 65 is subjected to increased interior pressure and is caused by the force of such pressure to move outwardly simultaneously with the outward movement of the diaphragm 2. The result is that the spring 70 is compressed against the abutment member 67 and the rod 60 is pulled outwardly so that the spring 63 is disengaged from one tooth of the ratchet wheel 50 and is carried outwardly a sufficient distance to engage the next succeeding tooth. Thereafter the gas supply valves are closed and the outlet valve is opened with the result that the gas escapes through the pipe 30 so that the pressure of the gas in the chamber of the casing 1 is reduced. The

spring 70 expands and augments the force exerted by the tendency of the diaphragm 65 to return to normal position as the pressure in the chamber of the casing 1 decreases 5 and causes movement of the rod 60 inwardly to cause a one step movement of the ratchet 50 on its pivot. It being understood that the lengths of the periods of darkness is dependent upon the periods of time that are 10 required for a sufficient amount of gas to flow into the chamber of the casing 1 to lift the diaphragm 2 to close the valve to which the supply gas pipe is connected, it will be obvious that if means is provided which 15 varies the amount of gas which enters the said chamber at and during certain intervals the lengths of the dark periods will be varied.

In the present construction, the perforations 52 in the ratchet wheel 50 are located at equal distances from each other and the distances between them are such that at every third depression or downward movement of the valve plate 17, the valve stem 46 is in alignment with a perforation 52 and in consequence thereof the valve closing plug 43 is not depressed. I have, therefore, provided a construction in which two short dark periods are followed by one long dark 30 period.

In Fig. 6 I have illustrated a construction in which the spring 70 shown in Figs. 1 and 2 for augmenting the action of the diaphragm 65 is omitted. In said Fig. 6 I 35 have provided a chamber 75 with which the outlet pipe 30 communicates. The said chamber 75 is closed by means of a diaphragm 76 which is located in parallel relation to a diaphragm 77 of substantially 40 less area, which closes the opening 78 in the side of the casing 1. The two diaphragms are separated from each other by means of a ring-like member 79 which serves as a clamping means for holding the 45 diaphragm 77 in position and as a supporting means for the diaphragm 76 which is clamped and held between the outer edge of the said ring-like member and the casing of the chamber 75. The ring 79 is provided with a hole 80 whereby the chamber within the same and between the diaphragms 76 and 77 is in communication 50 with the open air. The casing of the chamber 75 and the ring-like member 79 are 55 secured together and to the body of the casing 1 in any suitable and desired manner. The rod 60 is connected, as shown, to both of the diaphragms 76 and 77 for a purpose to be hereafter set forth. It will be understood 60 that when the valve which controls the flow of gas from the chamber of the casing 1 through the outlet pipe 30 is closed the pressure in the chamber 75 is reduced to that of the atmosphere at normal pressure. This 65 is due to the fact that the pipe 30 leading

from the said chamber to the burner is in communication at the burner with the outside air. At such time the gas is entering the chamber of the casing 1 through the supply pipe 31 or through the latter and the pipe 40 simultaneously with the result that the pressure in the said chamber reaches a point in excess of the normal atmospheric pressure in the chamber 75 so that the diaphragms 76 and 77 are moved outwardly 70 carrying therewith the rod 60. Upon the closure, however, of the valve or valves which control the flow of gas into the chamber in the casing 1 and the opening of the valve of the pipe 30 communication is established between said chamber and the chamber 75 so that the gas pressure within the said two chambers is equal. By reason, however, of the fact that the area of the diaphragm 76 which closes one side of the chamber 75 is 75 substantially greater than the area of the diaphragm 77 which closes the opening 78 leading from the chamber in the casing 1 and of the further fact that the chamber between the said diaphragms is in communication with the open air, the force exerted by the said diaphragm 76 by reason of the gas pressure thereon is greater than the opposing force of the diaphragm 77 so that the resultant of the two forces is in a direction to cause movement of both of the said diaphragms 76 and 77 and the rod 60 and the parts connected thereto inwardly or toward the right, having reference to Fig. 6, to cause movement of the ratchet wheel 50. Each inward movement of the diaphragms and the rod 60, as thus stated, causes a one 80 step movement of the ratchet wheel 50. 90

As already pointed out, in the construction as illustrated in which the valve for controlling the supply of gas through the supplemental pipe 40 is opened simultaneously with the opening of the valve for controlling the inflow of gas, except when the valve stem 46 is in alignment with one of the perforations 52 in the ratchet wheel 50, I have two relatively short dark periods and one relatively long dark period alternating of course with light periods. In case, however, it should be desired to have two relatively long light periods followed by a single relatively short light period, I can accomplish this result by merely reversing the position of the valve mechanism and the ratchet 105 110 115 120 125 130 50 associated therewith with respect to the valve plate 17 so that, except when the valve stem 46 is in alignment with a perforation 52 in the ratchet wheel 50, gas is permitted to enter the chamber of the casing 1 during the time that the valve of the outlet pipe 30 is opened instead of when the valve of the gas supply pipe 31 is opened. This relative arrangement of the ratchet wheel 50 and the valve construction associated therewith for controlling the inflow of gas from the pipe

40 with respect to the valve plate 17 is not illustrated because such change in relationship does not change the actual construction. The same construction and mechanism 5 are merely employed for opening the controlling valve for the auxiliary supply pipe during the periods when the outlet valve of the pipe 30 is opened instead of when the inlet valve of the supply pipe 31 is opened.

10 It is clear that if the auxiliary pipe 40 and the outlet pipe 30 are open at the same time, gas will be flowing into the chamber of the casing 1 at the same time that it is flowing therefrom through the pipe 30 with the result that the outflow will continue for a 15 longer period than otherwise would be the case so that the lengths of the light periods are thus increased.

It will be seen from the foregoing description that the ratchet wheel 50 is actuated by mechanism controlled by forces due to the increase of pressure and reduction of pressure of the gas within the chamber of the casing 1 of the apparatus.

25 Having thus described my invention, I claim:—

1. In light signal apparatus, the combination of a casing having a chamber, means for supplying gas thereto, means for delivering the gas therefrom to a burner, means for controlling the flow of gas into and from the said chamber so that the inflow and outflow thereof may be caused to take place during periodic intervals, and 30 mechanism operated and controlled by the increase and decrease of pressure in the said chamber for causing a periodically increased flow of gas into said chamber, the said mechanism being independent of the said 35 mechanism operated and controlled by the increase and decrease of pressure in the said chamber for causing a periodically increased flow of gas into said chamber, the said mechanism being independent of the said 40 means for controlling the flow of gas into and from said chamber.

2. In light signal apparatus, the combination of a casing having a chamber, a gas outlet from said chamber for supplying gas 45 to a burner at intervals, a main supply pipe for conducting gas into the said chamber at intervals, means actuated by the increase and decrease of gas pressure in said casing to cause the said outlet and supply pipe to be 50 opened and closed, an auxiliary gas supplying means, and mechanism operated and controlled by the increase and decrease of pressure in the said chamber for causing the flow of gas from the said auxiliary source 55 into the chamber at intervals, the said mechanism being independent of the said means for causing the said outlet and supply pipe to be closed.

3. In light signal apparatus, the combination of a casing having a chamber, an outlet conduit for supplying gas to a burner, a conduit for supplying gas to the said chamber, means for alternately opening and closing the said conduits, auxiliary means for supplying gas to the said chamber, and mecha-

nism including a diaphragm operated and controlled by the increase and decrease of gas pressure in the said chamber for periodically permitting gas to enter the said chamber from the said auxiliary source.

70

4. In light signal apparatus, the combination of a casing having a chamber, a diaphragm for closing the said chamber, an outlet valve for controlling the delivery of gas to a burner, an inlet valve for controlling the supply of gas to the said chamber, a valve member having connection with the said diaphragm and oscillating between the said valves to open and close the same to control the outflow and the inflow of gas through the said valves, an inlet valve for controlling a supply of gas to the said chamber from an auxiliary source, and mechanism including an additional diaphragm controlled and actuated by the increase and decrease of pressure of gas in the said chamber for alternately opening and closing the said last mentioned valve for periodically permitting the flow of gas from the said auxiliary source into the said chamber.

80

5. In light signal apparatus, the combination of a casing having a chamber, a diaphragm for closing the same, an outlet from said chamber to supply gas to a burner, an inlet for supplying gas to said chamber, means having connection with the said diaphragm for alternately opening and closing the said outlet and the said inlet, an auxiliary inlet for supplying gas to the said chamber, a valve for closing the said auxiliary inlet, and means independent of the said diaphragm which is responsive to the increase and decrease of pressure in the said chamber and which means controls and actuates mechanism to open the valve of the 95 said auxiliary inlet at intervals whereby gas is permitted to enter the said chamber periodically through the said auxiliary inlet.

100

6. In light signal apparatus, the combination of a casing having a chamber which is closed by a diaphragm, movement of which is caused by the varying pressures of gas in the said chamber, an outlet from said chamber for supplying gas to a burner, an inlet for supplying gas to the said chamber, a valve opening and closing member actuated by the said diaphragm for alternately opening and closing the said outlet and inlet, an auxiliary inlet for supplying gas to said chamber, a valve for closing the said inlet, 110 means associated with the said valve closing member for controlling the valve of the said auxiliary inlet, and mechanism actuated independently of said diaphragm and controlled by the varying gas pressures in the 115 said chamber for actuating the means for controlling the said auxiliary valve whereby the periods between the opening of the latter may be varied.

120

7. In light signal apparatus, the combina-

125

130

tion of a valve casing having a chamber which is closed by a diaphragm which is responsive to the varying gas pressures in the said chamber, an outlet valve for controlling the delivery of gas to a burner, a main inlet valve for controlling the delivery of gas to the said chamber, a valve closing member actuated by the said diaphragm to open and close the said valves, an auxiliary valve for controlling an auxiliary supply of gas to the said chamber, a rotatable device for opening the said auxiliary valve at intervals, and mechanism including an additional diaphragm operated and controlled by the varying gas pressures within the said chamber for causing rotation of the said device.

8. In light signal apparatus, the combination of a casing having a chamber which chamber is closed by a diaphragm which is responsive to the varying gas pressures in the said chamber, an outlet valve for controlling the delivery of gas to a burner, a main inlet valve for controlling the delivery of gas to the said chamber, a valve member connected to the said diaphragm and actuated thereby for opening and closing the outlet and the inlet valves, an auxiliary valve for opening and closing an auxiliary gas supplying conduit, a rotatable device movable with the said valve closing member for opening the said auxiliary valve, the said device being provided with means whereby predetermined intervals between the opening of the said auxiliary valve differ in length from other such intervals, and mechanism independent of the said diaphragm which mechanism is actuated by the varying pressure of the gas within the chamber for causing rotation of the said device.

9. In light signal apparatus, the combination of a casing having a chamber which chamber is closed by a diaphragm the said diaphragm being responsive to the varying gas pressures in the said chamber, an outlet valve for controlling the delivery of gas to a burner, a main inlet valve for controlling the delivery of gas to the said chamber, a valve member oscillating between the said valves for opening and closing the same the said valve member being actuated by the said diaphragm, a valve for controlling the flow of gas into said chamber from an auxiliary source, a rotatable device supported upon the said valve member provided with means whereby the said auxiliary valve is held open during certain predetermined intervals when the said valve member occupies one of its two positions, and mechanism operated and controlled by the varying gas pressures in the said chamber for causing rotation of the said device.

10. In light signal apparatus, the combination of a casing having a chamber which is closed by a diaphragm which diaphragm is responsive to the varying gas pressures in

the said chamber, an outlet valve for controlling the delivery of gas to a burner, a main inlet valve for controlling the delivery of gas to the said chamber, a valve member connected to the said diaphragm and actuated thereby for opening and closing the outlet and the inlet valves, an auxiliary valve for controlling the flow of gas into the said chamber from an auxiliary source, a second diaphragm responsive to the varying gas pressures in the said chamber, and mechanism intermediate the said diaphragm and the said auxiliary valve for causing the opening of the latter at predetermined intervals.

11. In light signal apparatus, the combination of a casing having a chamber, an outlet valve for controlling the delivery of gas to a burner, an inlet valve for controlling the delivery of gas to the said chamber, a valve member oscillating between the said valves for opening and closing the same, an auxiliary valve for controlling the flow of gas into the said chamber from an auxiliary source, a ratchet wheel carried upon the said valve member, which ratchet wheel is provided with means whereby the said auxiliary valve may be periodically opened, and mechanism operated by the varying pressures in the said chamber for causing rotation of the said ratchet wheel, the said mechanism being independent of the said oscillating valve member.

12. In light signal apparatus, the combination of a casing having a chamber, which chamber is closed by a diaphragm, which diaphragm is responsive to the varying gas pressures in the said chamber, an outlet valve for controlling the delivery of gas to a burner, an inlet valve for controlling the delivery of gas to the said chamber, a valve member connected to the said diaphragm and actuated thereby for opening and closing the outlet and the inlet valves, an auxiliary valve for controlling the flow of gas into the said chamber, and a device movable synchronously with and also independently of the said valve member and having means whereby the auxiliary valve is opened a predetermined number of periods when the said valve member occupies one or the other of its positions and is not opened during a succeeding period when the said valve member occupies such position.

13. In light signal apparatus, the combination of a casing having a chamber which chamber is closed by a diaphragm, valves for controlling the inflow and outflow of gas into and from the said chamber, a valve member having connection with the said diaphragm and actuated thereby to alternately open and close the said valves, an auxiliary valve for controlling a flow of gas into the said chamber from an auxiliary source, said auxiliary valve having a valve stem, a

ratchet wheel supported upon the said valve member in operative relation to the said auxiliary valve, the said ratchet wheel having perforations at intervals therein which 5 are adapted to be moved into alinement with the said auxiliary valve stem, a second diaphragm which is responsive to the action of the varying gas pressures in the said chamber, and a member having connection with 10 the said second diaphragm and being movable therewith and being in engagement with the said ratchet wheel to cause rotation thereof to bring the said perforations in the said ratchet wheel and the spaces between 15 the same into successive alinement with the said auxiliary valve stem.

14. In light signal apparatus, the combination of a casing having a chamber, an outlet valve for controlling the delivery of gas 20 from said chamber, an inlet valve for controlling the delivery of gas to the said chamber, a valve member oscillating between the

said valves for opening and closing the same, means for causing oscillation of said valve member, an auxiliary valve for controlling the delivery of gas into the said chamber from an auxiliary source, a ratchet wheel provided with means whereby the said auxiliary valve may be periodically opened, and mechanism operated by the varying 25 pressures in the said chamber for causing rotation of the said ratchet wheel, the said mechanism including a tension spring, the said mechanism being independent of the said oscillating valve and the means for 30 causing oscillation thereof.

In testimony that I claim the foregoing as my invention, I have hereunto signed my name this 2nd day of April, A. D. 1912.

GUSTAF DALÉN.
